UNITED STATES PATENT OFFICE.

FRANK VOIGTMANN AND SILAS H. POMEROY, OF CHICAGO, ILLINOIS.

FIREPROOF WINDOW.

SPECIFICATION forming part of Letters Patent No. 691,211, dated January 14, 1902.

Application filed November 12, 1900. Serial No. 36,262. (No model.)

To all whom it may concern:

Be it known that we, FRANK VOIGTMANN and SILAS H. POMEROY, citizens of the United States, residing at Chicago, in the county of Cook and State of Illinois, have invented certain new and useful Improvements in Fire-proof Windows, of which the following is a specification.

This invention relates to improvements in windows, and refers more specifically to improvements in fireproof windows having sheet-metal sash and casings, certain features of the invention, however, being applicable to windows of other construction.

Among the salient objects of the invention are to provide an improved construction in the pivotal support, whereby the sash is movably united with the casing in such manner as to enable it to be almost completely reversed in its bearings, while at the same time it is so supported as to automatically close fully and promptly when released; to provide improvements in the details of construction of both the sash and the window-casing which render these structures more strong and rigid and at the same time enable them to be economically manufactured; to provide an improved construction whereby the joints between the sash and casing are more effectually sealed or weathered, and in general to simplify and improve the details of construction.

To the above ends the invention consists in the matters hereinafter described, and more particularly pointed out in the appended claims, and will be readily understood from the following description, reference being had to the accompanying drawings, in which—

Figure 1 is a perspective view showing the window-casing with the sash arranged therein in closed position and viewed from the inside. Fig. 2 is a view similar to Fig. 1, showing the upper sash opened and oscillated into its reversed position. Fig. 3 is a horizontal sectional view, taken on line 3 3 of Fig. 2, through the casing only. Fig. 4 is a view similar to Fig. 3, taken on line 4 4 of said Fig. 2. Fig. 5 is a horizontal sectional view taken on line 5 5 of Fig. 6 and looking downwardly, said view showing the socketed member of the pivotal support in plan. Fig. 6 is a face view of the inside of the casing, showing in side

elevation the socketed member of the pivotal support. Fig. 7 is a similar face or side view of the sash equipped with the pivot member of the pivotal support. Fig. 8 is a horizontal sectional view, taken on line 8 8 of Fig. 1, through the sash only and showing the pivot-bolt in top plan. Fig. 9 is a horizontal sectional detail taken on line 9 9 of Fig. 6 and 60 showing, on a somewhat enlarged scale, the detail of the connection between the pivot-socket member and the window-casing at one point. Fig. 10 is a horizontal sectional view, taken on line 10 10 of Fig. 1, through the side 65 rail of the sash only. Fig. 11 is a view taken on line 11 11 of said Fig. 1, showing the manner in which the glass is seated directly in the casing instead of within a separate sash; and Fig. 12 is a perspective view of the pivot-socket 70 casting.

In the present embodiment of the invention the upper sash of the window is made movable, while the lower sash is constructed as an integral part of the window-casing structure—i. e., the window-lights are set in an inner frame formed integrally with the main part of the casing.

Referring to the drawings, 1 designates as a whole the window frame or casing, which is of hollow sheet-metal construction and comprises the side casings, (designated 2,) top and bottom end casings 3 4, respectively, and an intermediate cross rail or member 5. The upper and lower portions of the side frames 85 2 differ somewhat in cross-sectional form, as best indicated in Figs. 3, 4, and 11, each side casing comprising an outer lateral wall 6, provided at a point intermediate of its width with an outwardly-extending flange 7, which 90 is adapted to be seated in the wall or setting in order to anchor the frame in the window-opening, an inner face-wall 8, provided with a rabbet or retreated portion 8', and an opposite or outer face-wall 9, likewise provided 95 with a rabbet or retreated portion 9', the three sides referred to being made of uniform construction throughout the entire length of the side casing. The inner wall or face, against which the movable sash fits in the upper part 100 of the casing and within which the glass is fitted in the lower part of the casing, is differently constructed at its upper and lower portions, the former, as indicated at 10, Figs. 3

and 4, forming a substantially plain surface, while the latter or lower portion is provided with a rabbet formed by the parts or surfaces 11 and 11' and a face portion proper, (designated 13.)

The swinging sash (designated as a whole 14) is pivotally mounted upon a transverse axis located about midway of its height between the side frame members of the casing, 10 and weathering-flanges are provided so arranged that when the sash is in closed position the joint between the side casing and the sash will be overlapped by said weather-flanges except for a short interval at the 15 points where the pivot-sockets are seated, as shown clearly in Fig. 1. Those portions of the weathering-flanges which are located above the pivots (designated 15 in the drawings) are formed upon and integral with the 20 side rails of the sash, while the weathering flanges or strips below said pivots (designated 16 in the drawings) are formed upon and integral with the side casings of the frame. In order to provide the weathering-flange 16 25 upon the casing member, the sheet metal is extended out at the angle formed at the junction of the surfaces 8' and 10 a distance equal to the desired width of the weathering-flanges and folded upon itself so as to 30 form a double-thick flange, as best indicated in sectional Fig. 4, this flange being preferably and as shown herein made concave on its inner surface, which rests against the sash when the latter is closed in the position 35 indicated in dotted lines in said Fig. 4 and correspondingly convex on its outer surface. In order to dispose of the metal necessary to form this flange along the lower half of the sash, it is flattened down against the upper 40 half of the face of the sash-opening, as indicated at 16' in Fig. 3, the differences in construction between the parts of the side casing above and below the pivots being indicated clearly in Figs. 3 and 4. The upper 45 end casing member 3 is substantially in cross-sectional form like that indicated in Fig. 3, except that the flattened-down portion 16' is omitted, while the cross-rail 5 is provided with a flange 16, constructed substantially as 50 shown in Fig. 4, so as to overlie the joint formed between the lower end of the sash and said rail.

The inner lateral face of the side casing at the lower part of the frame and within which 55 the glass is set without the interposition of a sash is constructed as shown in Fig. 11—that is to say, that part of the metal which forms the weathering-flange in the upper part of the side casing is disposed of by making the face 60 portion 8' somewhat wider, so that the face portion 11' is somewhat retreated relatively thereto, and the edge of the glass 17 is arranged to rest directly against this retreated portion and against the face portion 11 of the rabbet. 65 In the preferred construction shown one of the longitudinally-extending clenched joints of the frame is arranged to come at the angle

of the rabbet 11 11' and is constructed to form an internal flange 18, which serves to reinforce and render extremely rigid that part of the face against which the edge of the glass rests—a feature obviously of some importance. In order to secure the edge of the glass in position within the rabbet in a strong and reliable manner not apt to be affected by exposure of the window to fire, ears or clips 19 are struck out of the face 11 of the rabbet, so as to stand at right angles thereto in the position shown in Fig. 11, which clips are subsequently bent down against the outer face of 80 the glass, as indicated in dotted lines at 19'. It will be understood that the faces of the lower and middle rails 4 and 5, respectively, which receive the corresponding edges of the glass, are constructed substantially like the 85 corresponding faces of the side rails and need not, therefore, be particularly detailed.

Describing now the construction of the movable sash 14, the upper and lower portions of the side rails thereof are of somewhat 90 different construction, as indicated clearly in Figs. 8 and 10, the former figure representing the cross-sectional form of the sash above the pivotal support and the latter below the same. As will be seen by these figures, a flange or 95 weathering 20, shaped like the weathering 16, hereinbefore described, is provided along the inner side face of the rail above the pivotal support, while the surplus metal which forms this flange along said upper portion is flattened down against the face of the lower portion, as indicated at 21. The top rail of the sash is constructed like the upper portion of the side rail, while the bottom rail of the sash is substantially like the lower portion of the side rail, with the exception that the surplus fold of metal 21 is or may be omitted. The inner lateral face of the sash throughout its entire circumference is provided with a rabbet, as indicated at 22 23, Figs. 8 and 10, within 105 which the glass is seated and held by means of clips 24, formed and arranged substantially as are the clips 19, hereinbefore described.

Describing now the pivotal support where- 115 by the sash 14 is movably supported within the window-casing and referring more particularly to Fig. 12, 25 designates as a whole a casting adapted to be secured within and against the inner lateral face of the casing at 120 a point approximately midway of the height of the sash, as indicated in Figs. 1 and 2, said casting comprising an upright bar-shaped portion 26, provided at each end with screw or bolt apertures 27, a main body portion 28 125 of irregular outline and provided with a curved outwardly and downwardly extending pivot socket or slot 29, and a securing-ear or extension 30 upon said main body, at the end thereof opposite the bar portion 26, and 130 likewise provided with a screw or bolt aperture 31. This casting is seated within and against the inner lateral face of the casing, with its bar portion in register with the rab-

bet 8' and with its main body extending within an aperture formed in the face of said rabbet and resting with its outer face directly against the lateral wall 10, as indicated clearly in Figs. 5 and 6, the pivot-slot occupying a position with its outer and lower end in register with the pivotal axis of the sash when the latter is in a fully-closed position and extending obliquely upwardly and inwardly 10 from this point to a point near the inner edge of the casting, as best indicated in Fig. 6. The casting is securely mounted in this position by means of bolts 32, extended through the bar portion, through a filling-block 33, seated in the rabbet 8', and through the wall of the casing, as indicated at 34, while its outer end ear 30 is secured to the face portion 10 of the casing by means of a screw-headed bolt 35, inserted therethrough and engaging 20 said ear. In order that this bolt 35 may lie flush with the outer face of the casing, the margin of the aperture in the casing through which said bolt is inserted is countersunk inwardly, so as to lie within the correspondingly-countersunk bolt-aperture in the ear 30, (see particularly detail Fig. 9,) and the screw-threaded bolt is made of sufficiently smaller diameter to fit within this countersunk recess and lie flush with the face of the 30 casing, as indicated at 36.

Referring to Figs. 7 and 8, 37 designates the pivot whereby the sash is supported from the socket-casting 25, said pivot being conveniently and as shown herein formed integrally 35 with a face-plate 38, which is adapted to be secured against the outer lateral face of the side rail of the sash by means of screw-bolts 39. The outer end portion 37' of said pivot forms the pintle or engaging portion which 40 is adapted to enter and engage the slot 29 of the socket-casting, while the opposite end 37" is arranged to extend entirely through the side rail and is provided with a nut 40, threaded thereon and adapted to rest against the 45 inner surface of the side rail. It is to be particularly noted in this connection that the location of the pivot 37 relatively to the plane of the sash is such that when the sash is in approximately upright position and closed or 50 approaching its closed position the center of gravity of the sash is well outside of the pivotal axis of the same, this being due to the fact that the glass is set well outside of said pivotal axis. This is a feature of the utmost 55 importance in a structure of this character, for the reason that it insures the prompt and complete closing of the window and causes the sash to rest snugly against its seat, so that the weathering forms an effectual sealing for 60 the several joints around the sash and between it and the casing.

In order that the joints covered by the weathering may be more effectually sealed, the strips of fold or analogous packing material are secured within the hollow sides of the several weathering-flanges, as indicated at 41 in the several figures of the drawings.

Inasmuch as part of the weathering is upon the sash and part upon the casing or main frame and in order to provide for the pivotal movement of the sash within the casing, the weathering is interrupted for a short distance opposite each pivot-socket, as indicated clearly in Figs. 1 and 2. This interruption, however, extends for a short distance only, 70 and by reason of the slotted construction of the pivot-socket when the sash is pivoted over into a reversed position the lower ends of the weathering-flanges 21 upon the sash engage the upper end portions of the flanges 16 upon 80 the frame or casing and form stops, whereupon a further oscillation of the sash in the same direction causes its pivots to ride up the inclined curved slots until they reach and are arrested by the opposite ends of said slots. 85 This construction enables the sash to be reversed into the position shown in Fig. 2 and far enough so that its outer surface may be conveniently washed from the inside of the building, while at the same time the upwardly-inclined direction of the pivot-slots insures a prompt return of the sash to its closed position by gravity as soon as it is released. The provision of the slotted socket obviously enables the weathering-flanges to be brought 95 much nearer together—that is, enables the interrupted portion of the weathering opposite the pivots to be made much shorter or of less extent than would be the case were the slotted socket not employed. 100

In order that the sash may be readily engaged and disengaged from its pivotal support, the upper side of the slot 29 of the pivot-socket casting is cut away or interrupted throughout the greater part of its depth to 105 form an opening 29', through which the pivot may pass, and obviously when the sash is tilted into the reversed position (shown in Fig. 2) it may be disengaged from its sockets by simply lifting it so as to carry its pivots 110 out through said openings 29'. The slotted pivot-socket, which affords the shiftable pivot-bearing, therefore becomes of importance in this connection.

The window shown herein is of the automatic type, provided with a destructible retaining device adapted to be released by an abnormal degree of heat and when released to permit the movable sash to swing shut. In order that the window shall thus swing shut 120 when released, its pivotal axis is located somewhat above its transverse center of gravity, so that its lower end is substantially heavier than its upper end. The specific construction of said means for automatically releasing the window forms no part of the present invention, but may be briefly described as comprising a rod 42, provided at one end with an eye 43, adapted to be engaged with any one of a series of hooks 44 upon the lower 125 part of the window and at its opposite end engaged with a fusible link 45, which is in turn connected with the upper part or top rail of the movable sash, as indicated at 46. 130

It will be understood that the length of the rod 42 is such that when engaged with either of the hooks 44 the sash will be held in open or partially open position against its tendency to close by gravity, owing to its being pivoted upon an axis above its middle or center of gravity. The operation of the window has been fully set forth in connection with the description of the details thereof, and need not, therefore, be repeated.

While we have herein shown what we deem to be a preferred embodiment of our invention, yet it will be obvious that the details thereof may be modified to some extent without departing from the spirit of the invention, and we do not, therefore, wish to be limited to the precise details of construction shown except as they are made the subject of specific claims.

20 We claim as our invention—

1. In a window, the combination with a casing, of a sash pivotally mounted to oscillate upon a transverse axis, pivot-supports connected with the sash, inclined ways with which said pivot-supports are engaged, and a stop constituting a fulcrum upon which the sash is adapted to pivot while its pivot-supports proper are traversing said ways, whereby a pivotal movement is afforded for the 30 sash of increased angular extent.

2. In a window, the combination with a casing, of a sash pivotally mounted therein to oscillate upon a transversely-extending axis, pivot-supports therefor having engagement with inclined ways or slots, and a stop located on that side of the window with relation to which the slots are inclined upwardly and inwardly and in a plane below the upper ends of said slots, whereby the sash is capable of 40 bodily movement inwardly and outwardly and will be raised or lowered bodily when oscillated while engaged with said stop, as and for the purpose set forth.

3. In a window, the combination with a casing, of a sash pivotally mounted therein to oscillate upon a transversely-extending axis, pivot-supports therefor, inclined ways upon the casing with which said pivot-supports are operatively engaged, a stop located on that 50 side of the window-casing relatively to which said ways are inclined upwardly and inwardly, said stop being located below said ways, and constituting a fulcrum upon which the sash is adapted to pivot when resting in engagement therewith, and a stop located at the end of one of said ways and adapted to positively limit the extent of pivotal movement of the sash.

4. In a window, the combination with a casing, of a sash pivotally mounted therein upon

an axis extending transversely thereof and located intermediate its length, a weathering-seat against which said window is adapted to rest when closed, one portion of which is upon the casing and extends from points immediately below the pivots around the lower margin of the sash, and the other portion of which is upon the sash and extends from points immediately above the pivots around the upper margin of the sash, substantially as described.

5. In a window, the combination with a casing, of a sash pivotally mounted therein upon an axis extending transversely thereof and located intermediate the length of the sash, slotted supports with which the pivots of said sash have shifting engagement, and a weathering-seat against which the window is adapted to rest when closed, one portion of which is upon the casing and extends from points immediately below the pivots around the lower margin of the sash, and the other portion of which is upon the sash and extends from points immediately above the pivots around the upper margin of the sash, substantially as described.

6. As a new article of manufacture, a pivot-socket adapted to be secured upon one member of the meeting faces of a window-sash and the frame wherein the latter is seated, said casting being provided with a pivot-slot extending transversely with relation to the window-opening and inclined from its inner end downwardly and outwardly and forming an elongated support over which a pivot, mounted upon the opposite member, is adapted to travel, and being provided at the upper side of its inner end with an opening adapted to permit the withdrawal of the pivot from engagement with said slot and with closed ends which positively arrest and limit the extent of movement of said pivot within the slot, substantially as described.

7. In a window of the character described, the combination of the window-frame, as 1, the sash, as 14, pivotally supported therein, the inclined pivot-slots with which the pivots of said sash are engaged at opposite sides of the casing, the weathering-strip, as 16, upon the frame and extending around the lower half of the sash-opening, the weathering-strip, as 15, upon the sash and extending around the upper half of the latter, and the destructible retaining device for holding the sash in open position, combined and operating substantially as set forth.
